Sister's Patent

The invention referred to in this Sister's Patent and making part of the invention is a description in the name of the said Walter Jones himself of his improvement in the machine for levelling trunks for carriage within a truck, particularly a sheep truck.

This invention is an improvement in a machine already patented as far as the purpose above specified; and this improvement consists in elevating or lowering the third or upper roller so that it may be at any time required, keeping it at all times parallel with the other two rollers, which is effected by the machinery hereinafter described.

This machine consists of a truck or platform of plank supported by four legs, one on each side of this truck a piece of plank is placed edgewise, at the clear distance of the length of the rollers to be used and of sufficient width and thickness to resist any strain that may be applied in use. On the upper edges of this plank, several indent or half holes are made in the plates of iron supported by them and the whole bolted through the truck by four screw bolts, the rollers having each a crank are placed upon wherever you desire work in the indent or half holes at any required distance from the centre, so that one crank may be on each side. The third or upper roller which lies directly over the centre and parallel with the other two is supported by its guides in the heads of two iron bolts which pass perpendicular to them through the plank and receive upon their lower ends, so these nuts are placed equal distances and are worked by a centre wheel which is operated by a crank and serves to raise or lower the upper roller in any position to any particular work.

This wheel the pinions of which are supported upon the bottom of the truck by a plate; & other with the wheel of pinions which are by head screw bolts, on which the nuts of which constitute the principal means of the improvement.
